UNITED STATES PATENT OFFICE.

JOHN C. HENDRICKSON, OF PHILADELPHIA, PENNSYLVANIA.

COMBINED REGISTER BACKING AND DAMPER.

No. 884,088.

Specification of Letters Patent.

Patented April 7, 1908.

Application filed February 16, 1907. Serial No. 357,781.

To all whom it may concern:

Be it known that I, JOHN C. HENDRICKSON, a citizen of the United States, residing in the city and county of Philadelphia, State of Pennsylvania, have invented a new and useful Combined Register Backing and Damper, of which the following is a specification.

My invention relates to a new and useful 10 combined register backing and damper and consists in providing side plates for the register frame which conform to the sizes of the hot air flues in which they are to be situated so that they do not obstruct the said hot air 15 flue.

It further consists in pivotally mounting a flue damper in said sides.

It further consists in providing means adapted to pass through the face of the register 20 for actuating said flue damper.

It further consists of novel details of construction all as will be hereinafter fully set forth.

Figure 1 represents a perspective view of a 25 combined register backing and damper embodying my invention. Fig. 2 represents a vertical sectional view thereof, showing the device in position. Fig. 3 represents a rear elevation showing the device when used in a 30 hot air flue wider than the register backing.

Similar numerals of reference indicate corresponding parts in the figures.

Referring to the drawings:—in the present construction of registers the frame of the 35 register is supported by the wall and the damper for the flue is mounted above the register with the means for actuating the same projecting through the wall in which is usually placed a cup where the actuating 40 means projects. I have found in practice that in order to install registers considerable time is expended in placing the same properly in position, that the plaster sometimes accumulates to too great an extent in the 45 flues and in some cases, the frame falls into the flue with consequent ill results. In addition, where the dampers are placed above the register in the flue, should the damper become broken or disarranged, it is necessary 50 in nearly every instance, to break the plaster and paper in order to replace the said damper. My invention is designed to overcome these difficulties and by reason of placing the flue damper in the backing which is suitably con-

nected with the register frame the entire device 55 can be removed from its position in the wall without destroying the latter or the paper and can be quickly replaced in position without fear of its falling into the flue.

In the drawings I have shown a construction 60 for carrying out my invention but it will be evident that the arrangement of the parts may be varied and other instrumentalities used, which will accomplish the same results and I do not, therefore desire to be 65 limited to the construction as herein shown and described.

1 designates the register frame of any desired construction to which is movably attached the front plate 2 thereof, said plate 70 being adapted to be secured to said frame in any manner, preferably by screws, and said frame being provided with the register dampers 3 which are preferably pivotally mounted therein, in any desired manner and 75 which can be actuated by the pin 4, projecting beyond the face of the register in any desired manner, it being understood that in one position the dampers 3 open the register allowing the passage of hot air into the room 80 and in the other position entirely close off the register.

Connected in any desired manner with the frame 2 is the backing 5 which can be made of any desired material, as for example galvanized iron, said backing being preferably formed of substantially the shape and size of the register frame in order to frictionally engage the same, whereby it is supported. Projecting from the backing 5 are sides, or wings 90 6 which extend from the backing, a distance equal to the width of the hot air flue in which they are to be situated, whereby it will be seen that when the parts are placed in position the backing and register frame are held in 95 position and prevented from falling into the flue. Pivotally mounted in the sides or wings 6 is the flue damper 7 which in the present instance is provided with the pins 8, projecting beyond each side thereof which 100 are adapted to enter suitable openings in the sides 6 which latter are inwardly curved at 9, in order to receive the said pins and the damper 7 is suitably cut away as at 10 in order to provide for the inwardly projecting 105 portions 9 of the sides. The said damper 7 is preferably made with the angular extension 11 which is adapted, when the damper

is in closed position to sufficiently overlap the upper portion of the backing to prevent passage of the hot air while the lower end of the damper is adapted to contact with the walls 5 of the flue in order to prevent passage of hot air at this point.

I preferably form the backing register frame of the size to correspond with the width of the hot air flue but in some instances 10 the said flue may be somewhat larger than the register frame and backing and in order to meet this difficulty I provide the extensions 12 on the sides which extensions can be bent outwardly as seen in dotted lines in Fig. 3 in 15 order to contact against the sides of the hot air flue and prevent passage of the hot air between the sides or wings and the sides of the hot air flue.

Pivots connected with the damper 7 is 20 the rod 13 which in the present instance is connected above the pivotal point of the damper and projects outwardly and through an opening 14 in the register face and is provided with a threaded end on which is 25 mounted the knob or handle 15 for ease in operating said rod. By pulling the said rod the flue damper will be opened and by pushing in the same the damper will be closed. By this means it will be seen that I provide 30 a register having the usual dampers for closing the opening thereof and with a backing which carries the flue damper so that all of the parts can be removed at one time and inserted in position. Also mounted upon the 35 rod 13 is a stop nut 16 which can be adjusted upon the threaded end of the rod 13, in order to limit the throw of the damper 7.

From the above it will be seen that I provide a combined backing and damper for registers, the backing being adapted to fit the flue, so that when the register is placed in position the walls of the backing contact 40 with the walls of the flue to prevent the register from falling into the flue and at the same time I provide a support for the flue 45 damper, whereby the same can be removed with the register. Any means for connecting the ends of the backing may be employed and in the drawings I have shown a pin 17. In 50 cases where the backing fits the flue, the flanges or extensions 12 can be cut off at a point indicated by dotted lines in Fig. 2 or they can remain as shown in Fig. 2.

Having thus described my invention, what 55 I claim as new and desire to secure by Letters Patent, is:—

1. In a device of the character described, a register frame, a backing mounted therein, having extended sides, said sides being of a 60 width equal to the width of the flue in which the same is to be placed, and extensions on said sides below the bottom of said frame and bendable laterally to contact with the sides of the flue.

2. In a device of the character described, a 65 register frame, a backing mounted therein, having extended sides, said sides being of a width equal to the width of the flue in which the same is to be placed, extensions on said sides below the bottom of said frame and 70 bendable laterally to contact with the sides of the flue, and a damper pivotally mounted in and confined between said sides at the upper ends thereof.

3. In a device of the character described, a 75 register frame, dampers therein, a backing mounted thereon and extended beyond said dampers and having portions at the bottom overlapped and connected together, and sides projecting from said backing beyond 80 the same to extend into a flue and having provision whereby said backing and frame are frictionally held within the flue said sides having extensions bent to contact with the sides of the flue to prevent passage of the hot 85 air.

4. In a device of the character described, a register frame, register dampers suitably mounted therein, a backing on said frame, sides extending therefrom beyond the bottom wall of the backing to fit the flue above and below said bottom wall, a flue damper pivotally mounted in said sides and means for operating said damper the sides of said 90 backing having lateral extensions to contact 95 with the sides of the flue to prevent passage of the hot air.

5. In a device of the character described, a register frame, register dampers suitably mounted therein, a backing on said frame, sides extending therefrom beyond the bottom wall of the backing to fit the flue above and below said bottom wall, a flue damper pivotally mounted in said sides and a rod 100 pivotally connected with said damper and extending through the register face the sides of said backing having lateral extensions to contact 105 with the sides of the flue to prevent passage of the hot air.

6. In a device of the character described, a 110 register frame, register dampers suitably mounted therein, a backing on said frame, sides extending therefrom beyond the bottom wall of the backing to fit the flue above and below said bottom wall, a flue damper pivotally mounted in said sides, a rod pivotally connected with said damper and extending 115 through the register face and an adjusting nut mounted on said rod the sides of said backing having lateral extensions to contact 120 with the sides of the flue to prevent passage of the hot air.

7. In a device of the character described, a register frame having movable front plate, dampers, a backing connected with said frame and of a shape and size to frictionally engage and support said frame and having 125 its sides extended inward beyond the bottom

of the backing, extensions on said sides beneath said bottom and bent laterally to engage the sides of the flue to prevent the upward passage of the hot air a flue damper 5 pivotally mounted in said sides below the upper ends thereof and to the rear of the register damper, and operating means for said flue damper extending through and supported in said front plate.
